Primary Examiner — Mehri F Bajoul(74) *Attorney, Agent, or Firm* — ScienBiziP, P.C.(57) **CLAIM**

The ornamental design for ball toy, as shown and described.

DESCRIPTION

FIG. 1 is a top, front, right side perspective view of a ball toy, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings depict portions of the ball toy that form no part of the claimed design. The dot-dash broken lines shown in FIGS. 1, 2, 6 and 7 are for the purpose of illustrating boundaries that form no part of the claimed design.

1 Claim, 7 Drawing Sheets(56)
